CASE FOR AN ELECTRIC METER

George D. Perkins and David E. Workman, both of Pasadena, Calif., assignors to Pendleton Tool Industries, Inc., Los Angeles, Calif., a corporation of Delaware

Filed Sept. 14, 1965, Ser. No. 86,992

Term of patent 14 years

(Cl. D26—1)

Fig. 1

Fig. 2

Fig. 4

FIG. 1 is a perspective view of a case for an electric meter embodying our new design;

FIG. 2 is a front elevational view thereof;

FIG. 3 is an end elevational view thereof;

FIG. 4 is a rear elevational view thereof;

FIG. 5 is a sectional view taken on line 5—5 of FIG. 4;

FIG. 6 is a perspective view of a meter case showing a modified embodiment of our new design;

FIG. 7 is a front elevational view of the meter case of FIG. 6;

FIG. 8 is an end elevational view of the meter case of FIG. 6;

FIG. 9 is a back elevational view of the meter case of FIG. 6;

FIG. 10 is a top plan view of the meter case of FIG. 6; and

FIG. 11 is an end elevational view thereof, with parts broken away, to the plane of the section line 11—11 of FIG. 9.

The essential features of our design are shown in full lines.

We claim:

The ornamental design for a case for an electric meter, substantially as shown and described.
